United States Patent Office

Des. 218,558
Patented Sept. 1, 1970

218,558

CART UNIT

Richard J. Rubin, 39 Dolphin Road,
Newton, Mass. 02159

Filed Sept. 16, 1969, Ser. No. 19,168

Term of patent 14 years

Int. Cl. D12—02

U.S. Cl. D14—3

FIG. 1

FIG. 3

FIG. 2

FIG. 1 is a perspective view of a cart unit showing my new design;

FIG. 2 is a side elevational view thereof; and

FIG. 3 is an end elevational view thereof looking from right to left at FIG. 1.

The side opposite that shown in FIG. 2 is the same as FIG. 2.

I claim:

The ornamental design for a cart unit, substantially as shown.
